(57) **CLAIM**

What is claimed is the ornamental design for a towel ring, as shown and described.

DESCRIPTION

FIG. 1 is a perspective view of a towel ring showing a new design;

FIG. 2 is a front view of the towel ring of FIG. 1;

FIG. 3 is a rear view of the towel ring of FIG. 1;

FIG. 4 is a right side view of the towel ring of FIG. 1;

FIG. 5 is a left side view of the towel ring of FIG. 1;

FIG. 6 is a top view of the towel ring of FIG. 1; and,

FIG. 7 is a bottom view of the towel ring of FIG. 1.

The components of the display shown in broken lines illustrate portions of the towel ring form no part of the claimed design.
